UNITED STATES PATENT OFFICE.

FREDERICK H. WESTON, JR., OF SCHENECTADY, NEW YORK, ASSIGNOR TO GENERAL ELECTRIC COMPANY, A CORPORATION OF NEW YORK.

FUSE.

964,592.

Specification of Letters Patent. Patented July 19, 1910.

Application filed April 10, 1902. Serial No. 102,258.

To all whom it may concern:

Be it known that I, FREDERICK H. WESTON, Jr., a citizen of the United States, residing at Schenectady, in the county of 5 Schenectady, State of New York, have invented certain new and useful Improvements in Fuses, of which the following is a specification.

The object of this invention is to provide 10 a fuse in which the certainty of extinguishment of the arc will be greater than with thermal cut-outs of types ordinarily employed.

Certain features of the invention may be 15 adopted in fuses of any class, but the invention is especially applicable to those of the cartridge type, in which a fusible conductor or strip is inclosed in a containing shell.

My improvements consist in employing 20 between the terminals a fuse length of curved, zigzag, serpentine, helical, spiral, or other devious contour, by which the path of the arc stream is increased in length in comparison with the straight-line distance be- 25 tween the terminals; and in order to prevent the gaseous products, when the fuse melts or vaporizes, from arcing across so as to follow another path than that determined by the contour of the fuse, I provide barriers of 30 some suitable form by which any tendency of the vapor to form such a different path is effectually prevented.

I have found the best results to materialize by inclosing the fuse of irregular confor- 35 mation in an absorptive material, which is insulating and refractory, and preferably consisting of fragments of comparatively small subdivision. For this purpose I have obtained good results with lime, granular 40 marble and similar products which are non- conductors of electricity, are very refractory to heat, and are poor conductors of heat. Thus the products of the fuse when it melts or vaporizes are driven by the developed 45 pressure into the pores or interstices of the porous material, cooling them and preventing the arc from holding over; and in this tendency the increased length of the fuse between the terminals is of very great assistance, the extinguishing effect being much 50 greater than with a fuse which is inclosed in a finely divided non-conducting material

and which extends through the same in a straight line.

My fuse also embodies structural im- 55 provements in the terminals of the cartridge, both in point of cheapness and effectiveness, as will be hereinafter set forth.

The several features of novelty will be 60 particularly described hereinafter and will 65 be definitely indicated in the claims appended to this specification.

In the accompanying drawings, which 65 illustrate my invention, Figure 1 is a sec- 70 tional elevation of a cartridge fuse embody- 75 ing my improvements; Fig. 2 is an end view of the same; Fig. 3 is a detail of the blank from which the terminal is formed; Fig. 4 shows a finished terminal; and Fig. 5 shows 70 one form of fusible conductor and leads. 75

1 represents a shell of fiber or other suitable insulating material in tubular form. This is commonly made of some organic material, such as fiber, by reason of ease of manufacture. In order to prevent the heat 75 of the fuse from damaging this casing, it is lined with a layer 2 of asbestos. On the ends of this shell are secured brass caps 3—3^a, being lagged fast by set-screws, as indicated. Each cap is provided with one 80 or more vent holes, as 4—4^a to prevent de- 85 struction of the cartridge in case of a short- circuit on extraordinary and sudden rise of pressure due to instantaneous volatilization of the mass of fusible material. The fuse 85 itself may be formed of any suitable mate- 90 rial, such as common fuse-metal formed of an alloy of lead and tin, or it may be made of a strip of sheet zinc or sheet aluminum, or even sheet copper. The form shown in 95 the drawing at 5, is a lead-tin fuse. This is soldered fast to lead wires 6—6^a, which may be formed of copper or other relatively less fusible material than the metal consti- 100 tuting the fuse strip, which in turn at the free ends is connected with the copper ter- 105 minals 7—7^a. These terminals are formed from a piece of sheet copper, a blank being first formed as indicated in Fig. 3, and then folded in the middle as indicated in Fig. 4, the four ears 8 of the blank being bent at right angles to the plane of the terminal, as indicated in Fig. 4. At the time the blank is struck holes 9 are punched, which,

when the blank is bent, lie at a distance from the ears 8, depending on the thickness of the end-caps 3—3^a, and through these holes are inserted cotter-pins 10 (see Fig. 2) 5 which fasten the terminals into the end-caps.

In assembling the parts of the fuse one end-cap is removed and one of the terminals inserted, as shown in Fig. 1, into the 10 other cap, and fastened with a cotter pin. The shell is then filled with the granular or finely divided material used to surround the fuse, and the other cap slipped over the free terminal and the set-screws driven in so as 15 to fasten the parts securely together.

The fuse shown in the drawings is a simple helix, the generating radius of which decreases near the ends. This may be widely varied however, and the helix may be made 20 of uniform diameter and may be made of varying pitch and of varying distance between the turns. The invention is however not limited to helical configuration, but may be of zigzag or undulating form, the several 25 bends being in the same or different planes as may be desired. The essential feature is that the distance between the fixed copper leads or between the fuse terminals may be considerably increased by the bent or irregular 30 shape of the fusible strip, forcing the arc, when the fuse melts, to traverse a much greater length in order to hold over than would be the case if a straight fuse strip were employed. When the fuse blows, the 35 melted or volatilized metal is driven by the pressure generated by heat and volatilization into the porous material, the increased length greatly increasing the resistance of the arc stream due to the unfused residual 40 products in the contracted channel or path between the terminals. This increased resistance of course renders the arc less tenacious and therefore contributes to its extinguishment.

45 I desire to have it understood that the several parts of the invention may be used separately if desired; for example, the improvements in the terminal may be used with straight fuses or fuses of any other 50 kind; similarly the fuse may be used with any kind of terminals.

What I claim as new and desire to secure by Letters Patent of the United States is,

1. The combination with an inclosing casing and an absorbent filling material, of a 55 fusible member extending therethrough and provided with portions bent transversely to its axis and lying in a plurality of planes, whereby upon melting thereof a hydrostatic head is produced at some point in the chan- 60 nel containing the molten metal.

2. A thermal cut-out comprising a sinuous strip of fusible metal, and a non-conducting absorbent material surrounding said strip.

3. A thermal cut-out comprising a receptacle, a helically bent strip of fusible material within said receptacle, and a non-conducting absorbent material carried by said receptacle and in contact with said strip. 65

4. A thermal cut-out comprising a shell 70 of insulating material provided at its ends with metallic contacts, a helically bent or undulating strip of fusible material extending through said shell and connected to said terminals, and a filling of non-conducting 75 absorbent material surrounding said strip.

5. A cartridge fuse comprising a shell, end-caps, terminals formed of sheet metal having bent lugs and adapted to be inserted from the inside of the cap, and a hole to 80 receive a lock-pin after the parts have been assembled.

6. The combination with an inclosing casing, of a fuse link within the casing and having a terminal projecting through the 85 wall of the casing and doubled over upon itself to form a rigid projecting fuse terminal.

7. The combination with a casing comprising a shell and a cap closing an open 90 end of the shell, of a fuse link within the casing and having a terminal projecting through the cap and doubled over upon itself to form a rigid projecting fuse terminal. 95

In witness whereof I have hereunto set my hand this 8th day of April, 1902.

FREDERICK H. WESTON, JR.
